UNITED STATES PATENT OFFICE.

JAMES J. GEBHARDT, OF CHICAGO, ILLINOIS, ASSIGNOR TO WODACK ELECTRIC TOOL CORPORATION, OF CHICAGO, ILLINOIS, A CORPORATION OF ILLINOIS.

CONTROL MECHANISM FOR ELECTRIC TOOLS.

Application filed April 13, 1923. Serial No. 681,950.

The invention pertains to electric tools such as drills, hammers, portable grinders, etc. and has for its aim the provision of a controlling mechanism of advantageous character for tools of this type.

Portable electric tools now commonly in use are equipped with a switch mechanism for controlling the operation, which requires a manual operation both for setting the tool in operation and for stopping it. Because of the distinct manual operation required for stopping the tool, the user frequently neglects to cut off the current when he lays the tool aside so that it continues to operate idly. This results in unnecessary wear and tear and also presents a source of danger to the operator and his fellow workmen. Moreover, under some conditions it is very necessary that the tool be brought to an instant stop, but in the case of the tools in common use, as above mentioned, inasmuch as the stoppage requires the distinct operation of the switch, considerable time may elapse before it is possible to bring the tool to rest, and in this time serious injury may result to the operator as well as to the tool. To overcome the disadvantages resulting from the common type of control mechanism, it is desirable to employ a switch which automatically breaks the circuit when the operator releases the switch operating member. In some instances, however, the operator may desire to lock the switch in closed position so that the operator will be relieved of the necessity of holding the switch closed.

The object of my invention is to provide a controlling mechanism including a switch which tends at all times to move into open position, and means associated with the switch-operating member and arranged so that it may be set to automatically lock the switch in closed position or to permit the switch to move automatically into its open position.

A further and incidental object is to provide a switch mechanism associated with the handle of an electric tool and having a locking means which is especially adapted for convenient operation to release the switch instantly when occasion requires.

The objects of the invention thus generally stated together with other and ancillary advantages are attained by the construction illustrated in the accompanying

drawings forming part hereof. I have illustrated but one form of my invention, it being contemplated that various changes may be made by those skilled in the art without departing from the spirit and scope of the invention as expressed in the appended claims.

Figure 1 of the drawings is a side elevational view of an electric drill equipped with a controlling mechanism constructed in accordance with my invention. Fig. 2 is a fragmentary underside view of the controlling mechanism as applied to the side of the drill. Fig. 3 is a front side elevational view of the control device. Fig. 4 is an elevational view partly in section looking into the interior of the switch casing.

I have selected for purposes of illustration a portable electric drill comprising a casing 7 enclosing an electric motor 8 and suitable operative connections (not shown) between the motor and the drill chuck 9. 10 designates a handle at the upper end of the casing, and 11 and 12 designate side handles extending radially from the casing 7 at diametrically opposite sides thereof. The handle 11 is suitably fastened in a boss or enlargement 13, and the handle 12 is carried by a housing 14 for the switch designated generally by the numeral 15 (Fig. 4). Said housing is suitably secured to the side of the casing 7 as by means of screws 16. Electric current passes to the motor 8 through conductors 17, one of which passes into and out of the switch housing 14 for connection with the switch terminals in a well known manner.

The switch 15 herein shown comprises a plunger 18 slidable in a bracket 19 and connected by means of a coiled tension spring 20 with a pivoted yoke 21 constituting the movable switch contact. A pair of stationary contacts 22 (one only being herein shown) is mounted upon an insulated base plate 23 and connected with binding posts 24 to which extend the conductors 17. A coiled compression spring 25 normally holds the plunger 18 in its outermost position in the bracket 19, and in the reciprocation of the plunger the swinging contact 21 operates with a snapping action into and out of engagement with the stationary contacts 22.

To operate the plunger 18 to close the switch, a lever 26 is pivoted at 27 in the

lower portion of the housing 14 near the forward edge thereof. This lever 26 operates in a slot 28 formed in the lower side or edge wall of the housing, and the free end 5 of the lever has a foot or bearing portion 29 which rests slidably upon a head 30 of insulating material carried by the free end of the plunger 18.

It will be seen that in order to maintain 10 the circuit closed the operator, with the construction thus far described, must retain his hold upon the switch lever 26 which he can conveniently do because of the association of the switch with the handle 12. In Fig. 1 I 15 have shown in broken lines the switch lever as applied to the handle 10. In either case, the lever is held in its closed or inward position by a finger or the thumb of the hand upon the handle, and it will be apparent 20 that immediately upon the release of the lever the tool will come to rest. With this arrangement the tool is capable of operation with maximum safety to the operator, his co-workers and to the tool itself. However, 25 in order that the tool may be capable of operation so as to release both hands of the operator for other work and at the same time provide for the opening of the motor circuit with maximum ease and rapidity, I 30 provide a locking means for the switch comprising a retaining or hook member 31 pivoted at 32 near the free end of the lever 26 and on an axis parallel with the pivot 27 for said lever. The pivot 32 may be mounted in 35 an enlargement or rib 33 upon the lower forward side of the housing, the rib being suitably cut away or notched at 34 to receive the retainer member and permit of its swinging movements to be presently described.

40 The lower end of the member 31 has a portion 31^a extending rearwardly substantially at right angles to the main portion of the member and adapted to engage with a shoulder 35 formed by the lower end of a plate 36 which is fast upon the free end of the switch lever 26. Since the latter is made preferably of aluminum, the plate 35 45 is formed separately and made of steel or other suitable wear-resisting metal. A coiled expansion spring 37 is interposed between the retainer member 31 and the forward side wall of the switch housing so as to tend to force the hook 31^a against the plate 36 on the lever 26, whereby when the latter is operated to close the switch, the hook 50 will snap into engagement with the shoulder 35 to lock the switch lever and hence the switch in closed position. The spring 37 preferably encircles a pin 38 carried by the retainer member 31 and it enters a socket 39 in the forward side of the housing.

55 It will be observed that the retainer member 31 extends upwardly almost flush with the upper side of the housing and along the forward face thereof. The member is thus

in convenient position to be tripped by the hand of the operator on the handle 12, whereby to release the switch for movement into its open position. I have found in practice that the switch may be released 70 much more rapidly than is possible with switches of the non-automatic type which require a distinct manual operation to open the circuit. Thus with the present construction a mere touch upon the free end of the 75 retainer member is sufficient to release the lever 26 for outward movement.

If now it is desired to render the retaining or locking means inoperative, this may be done by means of a small slide plate 40 80 mounted upon the underside of the rib 33. Said plate is secured upon the rib 33 by means of a screw 41, being slotted centrally thereof to receive the screw. At one side of the slot the plate is extended forwardly to 85 form a finger 42 which is adapted to enter between the retainer member 31 and the adjacent wall of the housing, thus constituting an abutment for the upper portion of the retainer member to prevent it from swinging 90 into engagement with the shoulder 35 under the action of the spring 37. The plate has a central hump 40^a which is so positioned with respect to the screw 41 as yieldingly to resist sliding movement of the plate into either 95 extreme position.

It will be seen that by the provision of the retaining means which I have provided, the tool is capable of operation with the controlling mechanism semi-automatic, to provide a maximum safeguard against injury, or with the control mechanism automatically locked in position to maintain the circuit closed but permitting the instant release of the switch for movement into open position. Thus, in 105 either event, the possible injury to the operator and to the tool is minimized.

From a manufacturing standpoint the retaining device can be applied to the control mechanism at a practically negligible cost 110 and the construction is such that it will not wear out readily nor require frequent repair.

I wish especially to point out that the invention is not limited to the application of 115 my improved retaining device to switches of the specific character herein illustrated and described, nor to switches located upon the side of the tool as in the present instance, for it is contemplated that it may be used 120 wherever the switch is located whether it be upon the side of the tool, in the handle 10 or elsewhere.

I claim as my invention:

1. In an electric tool, the combination of 125 a switch having a swinging contact, a reciprocable operating member having a resilient connection with said contact to swing it, a spring tending to resist the movement of said operating member to move said contact 130

into closed position, an operating lever engaging said plunger to operate it, and means for locking the lever and thereby the switch in closed position.

5. 2. In an electric tool, the combination with a control mechanism comprising a switch having a swinging contact member, a plunger resiliently connected with said member, a spring tending to resist movement of said plunger in one direction, an operating lever pivoted at one end and operatively associated at its other end with said plunger, and means associated with said lever adapted to engage therewith automatically whereby 10 to lock said swinging contact member in closed or operative position.
3. In an electric tool, the combination with a control mechanism comprising a switch having a swinging contact member, a plunger resiliently connected with said member, a spring tending to resist movement of said plunger in one direction, an operating lever pivoted at one end and operatively associated at its other end with said plunger, 15 means associated with said lever adapted to engage therewith automatically whereby to

lock said swinging contact member in closed or operative position, and means for holding said retaining member in inoperative position.

30

4. The combination in an electric control mechanism of an operating member, and a device for locking the operating member in a predetermined position, spring means tending to move the device in one direction, and a slide plate movable into engagement with the lever to prevent movement of the lever by such spring means.

35

5. The combination in an electric control mechanism of an operating member, and a device for locking the operating member in a predetermined position, spring means tending to move said device in one direction, and a slide plate movable into engagement with the device to prevent movement thereof by 40 such spring means, said slide plate having means for resiliently holding it in either operative or inoperative position.

45

In testimony whereof, I have hereunto affixed my signature.

JAMES J. GEBHARDT.
